UNITED STATES PATENT OFFICE

2,050,473

ROTARY COMPRESSOR

Karl Steinmann, Winterthur, Switzerland

Application July 22, 1935, Serial No. 32,516
In Great Britain October 16, 1934

9 Claims. (Cl. 230—149)

I have filed an application in Great Britain on the 16th October, 1934.

The present invention relates to a rotary piston compressor.

5 The object of the invention is to provide an improved rotary piston compressor in which the suction space is very efficiently separated from the delivery space of the engine by resilient packing means. Another object of the invention is to 10 provide improved means for operating and packing the movable abutment of the compressor.

Two constructions embodying the features of the invention are shown by way of example in the accompanying drawing.

15 Figs. 1 and 2 show the first construction, Fig. 1 being a cross section through a rotary piston compressor having a positively controlled abutment slide, and Fig. 2 being a sectional elevation corresponding to Fig. 1.

20 Fig. 3 shows in cross section a second construction in which the sliding abutment plate is only controlled by springs.

Fig. 4 is a sectional elevation corresponding to Fig. 3.

25 Referring to the drawing, 1 designates a stationary casing in which is rotatably mounted a piston 2. According to the invention, this piston is formed at the point of contact with the casing with a flattened portion 4 and is also provided with a resilient packing cover 3 which is fixedly connected with the piston and therefore rotates with the piston. Between the packing cover 3 and the flattened portion 4 of the piston 2, a cavity or hollow space 5 is formed and this cavity 30 communicates with the working space by means of holes 6 arranged at the discharge side in the resilient cover 3. The rotary piston 2 provided with the packing cover 3 is eccentrically mounted upon its shaft 7, the shaft being, of course, arranged in the centre of the cylindrical casing. By this eccentric mounting of the rotary piston 2 upon its shaft 7 relatively to the casing 1, a scythe-shaped working space 8 is formed in the casing, which is divided by a sliding abutment 9 35 into a suction space and a discharge space. The suction space communicates with a suction conduit 15, this conduit being controlled by the rotary piston. The delivery space communicates with a delivery conduit 16, a valve 18 loaded by a spring 17 controlling the communication between the conduit 16 and the delivery space.

40 In the construction according to Figs. 1 and 2, the sliding abutment 9 is slidably and swingably mounted in the casing 1 by means of a rotary member 14 in which the abutment is adapted to

slide. The abutment is positively operated by means of two connection rods 12, 12, the inner ends of which engage cams 13 mounted on both sides of the rotary piston 2 upon the shaft 7. The abutment 9 is, moreover, provided with an additional packing strip 10 which is pressed by one or more springs 11 against the resilient cover 3 of the rotary piston. By the cooperation of the resilient packing cover 3 with the resilient packing strip 10, a very satisfactory and resilient packing is obtained between the suction and the delivery spaces of the compressor.

45 In the construction according to Figs. 3 and 4, the sliding abutment 9 slides radially in the casing 1 in a suitable long guideway, and the casing 15 is provided with one or more bores 19 in which are mounted springs 20, the pressure of which may be adjusted by means of set screws 21. In this construction too a very satisfactory packing is obtained between the abutment and the resilient cover.

I claim:

1. In a rotary piston compressor the combination of: a stationary casing; a rotary piston eccentrically mounted for rotation in the casing, 25 said piston being provided at the point of contact with the casing with a flattened portion and being also provided with a resilient cover, a cavity being formed between said flattened portion of the piston and said resilient cover; said resilient 30 cover having an opening affording communication between said cavity and the delivery side of said casing; a sliding abutment cooperating with said rotary piston; an admission conduit in said casing; and a discharge conduit in said casing. 35

2. In a rotary piston compressor the combination of: a stationary casing; a rotary piston eccentrically mounted for rotation in the casing, said piston being provided at the point of contact with the casing with a flattened portion and being also 40 provided with a resilient cover; a cavity being formed between said flattened portion of the piston and said resilient cover, said resilient cover having an opening affording communication between said cavity and the delivery side of said 45 casing; a sliding abutment cooperating with said rotary piston; an admission conduit in said casing; a discharge conduit in said casing; and means for positively operating said sliding abutment.

3. In a rotary piston compressor the combination of: a stationary casing; a rotary piston eccentrically mounted for rotation in the casing, said piston being provided at the point of contact with the casing with a flattened portion and being also provided with a resilient cover; a cav- 50

55

ity being formed between said flattened portion of the piston and said resilient cover, said resilient cover having an opening affording communication between said cavity and the delivery side of said casing; a sliding abutment cooperating with said rotary piston; an admission conduit in said casing; and a discharge conduit in said casing; said sliding abutment being hollow and provided with a sliding packing strip and with interiorly arranged springs pressing said packing strip against said resilient cover.

4. In a rotary piston compressor the combination of: a stationary cylindrical casing provided with inlet and outlet conduits; a central shaft in said casing; a rotary piston eccentrically mounted upon said shaft for rotation therewith, said rotary piston having at the point of contact with the periphery of the casing a flattened portion; a resilient cover fixed to said rotary piston and provided opposite the flattened portion of the piston with openings at the delivery side of the piston; a cavity being formed between said resilient cover and said flattened portion of the piston; a member rotatably mounted in said casing between the inlet and the outlet conduits; a slideable abutment slidably mounted in said rotary member; a packing strip slidably mounted in said abutment; springs within said abutment adapted to press said packing strip against said resilient cover; and means for positively operating said sliding abutment by rotation of the shaft.

5. In a rotary piston compressor the combination of: a stationary casing provided with an inlet and an outlet conduit; a central shaft rotatably mounted in said casing; a rotary piston eccentrically mounted on said shaft for rotation therewith, said rotary piston having a flattened portion at the point of contact with said casing; a resilient cover fixed to said piston, said resilient cover being provided with openings at the delivery side of the piston through which a cavity formed between the flattened portion of the piston and said resilient cover communicates with the working space of the piston; and a spring controlled slideable abutment plate between said inlet and outlet conduits.

6. A rotary piston compressor having a stationary casing and a rotary piston therein, characterized by the fact that the rotary piston is provided with a flattened portion and is also provided with a resilient packing cover which is fixed to the piston and is provided towards the delivery side with pressure relief openings, said rotary piston being mounted eccentrically upon a shaft concentrically mounted in the stationary casing in such a manner that a scythe-shaped working space is formed which is divided by a sliding abutment into a suction space and a delivery space, whereby the resilient packing cover, on the occurrence of the maximum pressure, that is at the end of the pressure stroke, will always lie under the sliding abutment, whereby an effective and

resilient packing or separation of the suction and delivery spaces relatively to each other is obtained.

7. In a rotary piston compressor the combination with a stationary casing, a rotary piston flattened at the portion nearest to the inside surface of the casing, the piston being eccentrically mounted for rotation in the casing, the surface of the piston being surrounded by a closed resilient cover, with a flexible part on the place where the piston is flattened, the cover part and the flattened piston part forming a hollow space which is provided at the pressure side with pressure compensating bores for keeping the rotor tight against the inside surface of the casing.

8. In a rotary piston compressor the combination with a stationary casing, a rotary piston flattened at the portion nearest to the inside surface of the casing, the piston being eccentrically mounted for rotation in the casing, the surface of the piston being surrounded by a closed resilient cover with a flexible part on the place where the piston is flattened, the cover part and flattened piston part forming a hollow space which is provided at the pressure side with pressure compensating bores for keeping the rotor tight against the inside surface of the casing, the eccentrically mounted piston forming a crescent-shaped working space in the casing, subdivided into a suction-space and expelling-space, a member rotatably mounted in said casing between the suction-space and expelling-space, a slideable abutment slidably mounted in said rotary member, a packing strip slidably mounted in said abutment, and springs within said abutment, adapted to press said packing strip against said resilient cover.

9. In a rotary piston compressor the combination with a stationary casing, a rotary piston flattened at the portion nearest to the inside surface of the casing, the piston being eccentrically mounted for rotation in the casing, the surface of the piston being surrounded by a closed resilient cover with a flexible part on the place where the piston is flattened, the cover part and flattened piston part forming a hollow space which is provided at the pressure side with pressure compensating bores for keeping the rotor tight against the inside surface of the casing, the eccentrically mounted piston forming a crescent-shaped working space, subdivided into a suction-space and expelling-space, a member rotatably mounted in said casing between the suction-space and expelling-space, a slideable abutment slidably mounted in said rotary member, a packing strip slidably mounted in said abutment, and springs within said abutment, adapted to press said packing strip against said resilient cover, the slideable abutment being controlled by two connecting rods, fixed to it and by two cams arranged at the faces of the rotor, concentric with same.

KARL STEINMANN.
